DESIGN FOR A FAN

Lydia B. Koch, New York, N. Y.

Application June 1, 1934, Serial No. 52,012

Term of patent 7 years

To all whom it may concern:

Be it known that I, Lydia B. Koch, a citizen of the United States, residing at New York city, in the county and State of New York, have invented a new, original, and ornamental Design for a Fan, of which the following is a specification, reference being had to the accompanying drawing, forming a part thereof.

ing my new design and representing the features of doll-heads;

I claim:

The ornamental design for a fan, as shown and described.

LYDIA B. KOCH.
